UNITED STATES PATENT OFFICE.

FREDERICK A. HANES AND WILLIAM STAPLES, OF DISTRICT OF MUSKOKA,
CANADA.

RATCHET-WRENCH.

No. 818,761.

Specification of Letters Patent.

Patented April 24, 1906.

Application filed January 20, 1906 Serial No. 297,047.

To all whom it may concern:

Be it known that we, FREDERICK A. HANES, agent, and WILLIAM STAPLES, carpenter, of the District of Muskoka, in the 5 Province of Ontario, Canada, have invented certain new and useful Improvements in Ratchet-Wrenches, of which the following is a specification.

Our invention relates to improvements in ratchet-wrenches; and the object of the invention is to devise a simple, cheap, strong, and durable wrench of this class which may be used for various purposes, either as a plain or ratchet wrench, depending on the 10 class of work it is desired to use it upon and which may be readily and securely held during use; and it consists, essentially, of a hollow socket provided with a suitable turning-knob secured to the top of the same, a lever-arm through which the socket extends, a gear-pinion secured to or forming part of the 15 socket and located in a recess in the arm, and spring-pressed coacting dogs and latches for same designed to coact with the gear-wheel, the parts being otherwise constructed and 20 arranged in detail, as hereinafter more particularly explained.

Figure 1 is a perspective view of our improved ratchet-wrench. Fig 2 is a view of 25 the ratchet-wrench turned up and broken away, so as to exhibit the construction thereof. Fig. 3 is an enlarged vertical section through the socket and knob and lever-arm.

In the drawings like letters of reference indicate corresponding parts in each figure.

A is a lever-arm provided with a jaw-like end A'. The arm A is provided at the opposite end with a recess A² and orifice A³.

B is a socket designed to contain a wrench 40 or any other tool. The socket B is provided with a gear-pinion B', attached to or forming part of the same and fitting within the recess A² in the arm A. A suitable set-screw B² is provided to hold the tool or wrench in place.

The arm A is provided with side recesses 45 A⁴, in which are pivoted the lever-pawls C C', either of such lever-pawls being designed to be brought into engagement by the springs C' with the gear-pinion E' and either one or 50 both being designed to be held disengaged by the pivotal clip C², which is swung over the end of the lever-pawl remote from the pinion when the disengagement of the lever-pawl with the pinion is desired.

C³ is a plate which fits over the lever-pawls 55 and having orifices C⁴, through which the socket extends.

D is a knob which is connected to the socket B by means of the divided plate E, which extends into an exterior groove in the 60 socket. One portion of the divided plate E is provided with a lug G, through which extends an adjusting-screw H, such adjusting-screw being threaded, where it extends through the lug. 65

The adjusting-screw H has an inner head H', which fits into a recess I in the socket B. The head H is withdrawable into a recess G' when it is desired to disconnect the knob from the socket. The set-screw would be so 70 withdrawn when it is desired to use the arm A and the wrench as a ratchet-wrench; but if it is desired to use the arm A as simply a means for holding the wrench in position and use the knob D for turning the socket, as 75 may be required where the work done is not heavy, the screw H would be turned so as to insert the head H' into the recess I in the socket, as indicated in Fig. 3. In this case, of course, the lever C would be disengaged 80 from the gear-pinion B'.

It will thus be seen that we are not only enabled to use our wrench as a ratchet-wrench, but it may be used also as a plain wrench, using the knob D as a means of turning, and such socket in such case would be 85 free to rotate in the orifice in the end of the arm A.

What we claim as our invention is—

In a wrench, the combination with the 90 arm having an orifice formed in the end thereof, of a socket extending through such orifice and a pinion secured in the orifice, spring-pressed pawl-levers engaging therewith, pivoted catches located near the ends 95 of the lever remote from the pinion, a knob provided with a divided plate extending into an annular groove in the socket and having a lug formed on one of the portions thereof, and adjusting-screws extending through the 100 lug and having an enlarged head designed to be brought into a recess in the socket or in the lug, as and for the purpose specified.

F. A. HANES.
WILLIAM STAPLES.
